Schacht Law Office, Inc.(57) **CLAIM**

The ornamental design for a multi-chine water craft, as shown and described.

DESCRIPTION

FIG. 1 is an isometric view of a water craft of the present invention, taken from an upper side end location;

FIG. 2 is a top plan view thereof;

FIG. 3 is a right side elevational view thereof where the opposing left side view is a mirror image thereof;

FIG. 4 is a bottom plan view thereof;

FIG. 5 is an elevational view of the first end thereof;

FIG. 6 is an elevational view of a second end thereof; and

FIG. 7 is an exploded pre-assembled plan view of the components that form the right side of the water craft when assembled. A mirror image of each piece forms the left side of the water craft when assembled; and, FIG. 8 is a pre-assembled plan view of one component that in combination with the components shown in FIG. 7 and a mirror image copy thereof form the water craft when assembled.
